UNITED STATES PATENT OFFICE

HERMAN J. BRENDLIN, OF NEW YORK, N. Y., ASSIGNOR TO THE HAYWARD COMPANY,
OF NEW YORK, N. Y.

EXCAVATING SHOVEL

Application filed May 19, 1930. Serial No. 453,560.

This invention relates generally to excavating shovels, and the improvements are directed to a novel combined shackle and sheave frame for use in connection with drag line buckets.

As will presently appear, it is proposed to provide a device of the above mentioned character adapted to support a sheave, through the intermediary of a sheave frame, the latter being cast integrally with said shackle, said shackle being further adapted to support a hoisting bridle formed from a single piece of chain.

Those skilled in the art to which this invention appertains are aware that at the present time it is universally the practice to pivotally connect a hoisting bridle at points disposed rearwardly of the centre of gravity of a drag line bucket, the upper ends of the two members comprising the bridle being attached to either a shackle or a sheave block. When secured to shackles, a sheave block is also made fast to the former, and such an arrangement necessitates making forged shackles, cutting both bridles the same length and finally welding the links at either end, the two upper links engaging the aforesaid shackles.

It is therefore the primary object of the present invention to provide a hoisting bridle formed from a single piece of chain and to combine the same with an integrally formed shackle and sheave frame, whereby a medial link of said bridle is housed and securely maintained in proper assembled relation within a recess formed in said shackle.

Another feature of the invention is the provision of a device of the character aforesaid, which tends to simplify the construction of a drag line bucket and which facilitates the operation thereof.

With these objects in view, together with others which will appear as the description proceeds, the invention resides in the novel formation, combination, and arrangement of

parts, all as will be described more fully hereinafter, illustrated in the drawings, and particularly pointed out in the claims.

In said drawings:

Fig. 1 is a side elevation of a drag line bucket embodying my invention.

Fig. 2 is an elevation of the combined shackle and sheave frame, supporting a sheave and having a link of a hoisting bridle positioned within a recess formed in said shackle.

Fig. 3 is a front elevation of the same.

Fig. 4 is a sectional view taken on the line 4—4 of Fig. 2, a portion of a hoisting bridle being also shown.

Fig. 5 is a fragmentary plan view of said shackle as seen at the left of Fig. 1.

Fig. 6 is a side elevation of said shackle but introducing a pivot element for supporting a sheave, said element being positioned within the fork of said shackle.

Fig. 7 is a front elevation thereof.

Fig. 8 is a rear elevation of a slightly modified form of shackle wherein the pivot is mounted exteriorly of the fork of the shackle, the recess or chain-holder portion being shaped to receive a horizontal link of the hoisting chain.

Fig. 9 is a side elevation of Fig. 8.

Fig. 10 is a front elevation thereof.

Fig. 11 is a sectional detail as viewed on the line 11—11 of Fig. 9.

Referring now more in detail to the accompanying drawings, wherein like characters of reference denote similar parts throughout the several views, let 10 indicate generally a drag line bucket, having the usual cutting edge 11 and lugs 12 arranged exteriorly of each side of said bucket; said lugs being adapted to pivotally receive the ends of a hoisting bridle 13 at a point disposed rearwardly of the center of gravity of said bucket, as indicated at 14. The usual hauling chains 15 extend from the front edges of the sides of said bucket for connection with

the hauling rope 16 and the holding rope 17, the latter being passed around the sheave 18 and extended for connection with the upper frontal portion of the bucket, as shown at 19. With the exception of the aforesaid hoisting bridle 13, the aforementioned parts are more or less typical in drag line bucket constructions.

Upon inspection of Figs. 2 and 3, it will be observed that my improved device comprises a body portion 20 which is bifurcated at the lower portion thereof to form an integral frame 21 for the reception of said sheave 18, the latter being suitably arranged within the furcations of said frame by means of a bolt 22, or the like, as clearly shown in Fig. 4. The upper portion of said frame is provided with apertured ears 23 to receive one end of a hoisting line 24, as indicated in Fig. 1.

As previously set forth the adoption of my novel combined shackle and sheave frame permits the use of a single piece of chain designed to serve as a hoisting bridle, and in view of this arrangement it no longer becomes necessary to provide two separate chain elements or to resort to welding operations hereinbefore referred to.

At this end, the body portion of said shackle is provided with a chain-receiving pocket or recess 25, the walls of said recess, that is, the top, bottom and rear portion thereof being angular in cross-section, (see Figs. 4 and 5), to snugly interfit with the links of said hoisting bridle 13. In view of this arrangement it is only necessary to slip the medial link 13c of said bridle 13 within said recess 25 to the position indicated in Fig. 5, whereupon a bolt 26 is passed through aligned apertures 27 and 28 in said shackle, whereupon said bridle is securely anchored in position. This arrangement permits facile disassembling of the aforesaid parts.

At the form shown in Figs. 6 and 7, the shackle portion is similar to that just described in that the chain-receiving recess 29, the apertured ears 30 and the bolt 31, all function as aforesaid. In this particular instance, however, the lower portion of the shackle 32 is forked, as indicated at 33, and provided with aligned apertures for the reception of bolt 34 carrying the member 35, the latter housing the sheave 18.

The shackle 36, shown in Figs. 8 to 11 inclusive, is provided with apertured ears 37 to receive one end of the hoisting line 24, the bolt 38 and chain-receiving pocket 39, functioning in the same manner as that set forth in the other forms, with the exception that said pocket 39 is recessed, as indicated at 40, to receive a horizontal link 13b of the bridle 13. The lower portion of said shackle 36 is forked, as shown at 41, (see Fig. 10), and a pin 42 passing through the aligned apertures thereof secures the two parts of the member

43 in the position indicated. It will be noted that said member 43 is positioned exteriorly of said shackle 36 and further that a pin 44 is passed through the lower apertured bosses of said member to affix the sheave 18 in the 70 location indicated.

While the foregoing sets forth the preferred embodiments of the invention it will be understood that minor changes are contemplated provided such alterations fall 75 within the spirit of the invention as defined in the appended claims.

I claim:

1. In a drag line bucket, the combination with a shovel, of a one-piece hoisting bridle 80 pivotally attached to said shovel, hauling means secured to the front of said shovel, a shackle having a recess adapted to receive a medial link of said bridle, a sheave carried by said shackle and a holding rope extending 85 from the front of the shovel running over said sheave to the hauling means.

2. In a drag line bucket, the combination with a shovel, of a one-piece hoisting bridle pivotally attached to said shovel, hauling 90 means secured to the front of said shovel, a shackle having a recess adapted to receive a medial link of said bridle, means for maintaining said link within said recess, a sheave carried by said shackle and a holding rope 95 extending from the front of the shovel running over said sheave to the hauling means.

3. In a drag line bucket, the combination with a shovel, of a one-piece hoisting bridle pivotally attached to said shovel, hauling 100 means secured to the front of said shovel, a shackle having a recess adapted to receive a medial link of said bridle, said recess presenting angular walls, a sheave pivoted to said shackle and a holding rope extending from 105 the front of the shovel running over said sheave to the hauling means.

4. A shackle having a recess adapted to receive a medial link of a hoisting bridle, said shackle presenting an integral frame to house 110 a sheave.

5. A shackle having a recess adapted to receive a medial link of a hoisting bridle and presenting a forked portion for the reception of a pivoted sheave-supporting member. 115

6. A shackle having a pocket provided with recesses for the reception of a horizontal medial link of a hoisting bridle, said shackle presenting a forked portion adapted to be embraced by a pivoted sheave-supporting member, a portion of said sheave projecting within the forked portion. 120

HERMAN J. BRENDLIN.
